UNITED STATES PATENT OFFICE.

CHARLES T. LA MONT, OF MILWAUKEE, WISCONSIN.

STOCKING MARKER.

Application filed March 14, 1927. Serial No. 175,397.

This invention relates to a stocking marker.

In the manufacture of full-fashioned stockings, it is the regular practice to knit the stockings on different machines as the leg portion and heel tabs are formed on a "legger." The fabric or blank must then be taken off the "legger" and the stitches transferred to the needles of a "footer." In order to facilitate the transferring operation of placing each stitch upon the needle bar of the "footer," it is customary to spread the rows of stitches, and this has always been done by a rigid, pointed tool which is run up and down the rows of stitches by the operator. These tools frequently catch in the stitches and cause a tear or break, thus damaging the full-fashioned stocking, or else rendering it wholly unsalable.

This invention is designed to overcome the defects noted above and objects of such invention are to provide a marker which is equipped with a yielding point, so that as the tool is run over a row of stitches the point will yield in the event that it catches and thus tearing or breaking of the stitches is wholly avoided.

Further objects are to provide a marker which is of extremely simple construction, of small size, so that it is neither bulky nor unwieldy, and which is so constructed that it may be used with the utmost facility.

An embodiment of the invention is shown in the accompanying drawings in which:

Figure 1 is a side elevation of the marker partly in section showing its position when in use;

Figure 2 is a plan view of the structure shown in Figure 1.

Referring to the drawings, it will be seen that the marker comprises a curved body portion 1 which is preferably slightly thickened, as indicated at 2, and tapered towards its forward end. This forward end is bored out to provide the cylindrical aperture 3 therein, and a spring 4 is slipped into the aperture. Thereafter, a yielding plunger 5 is slipped into the aperture and has its rear end bearing against the spring. It is to be noted from Figure 1 that the plunger has

a reduced portion 6 terminating in abrupt shoulders and that a set screw 7 is threaded through the body portion 2 and is adapted to engage the shoulders to prevent withdrawal or loss of the plunger 5.

The plunger 5 thus constitutes a yielding point for the marker and it is to be noted that its extreme end is conical, as indicated at 8, for its major portion and its tip is rounded so that the tip of the tool may be run up and down the row of stitches by the operator.

If, for any reason, the point should catch in the stitches, it will not tear the stitches, as the spring 4 freely yields and the plunger slides over the stitches without tearing.

If desired, the marker may be provided with an aperture 9 at its rear end adapted to receive a retaining cord worn by the operator, or else such aperture may be used for hanging the tool on a suitable hook.

It will thus be seen that a marking tool for stockings has been provided in which a yielding point is used so that the danger of tearing or breaking the stitches is avoided.

It will be seen further that the marker is not unwieldy nor is it bulky, and it may be used with the same facility as the usual rigid markers.

Although the invention has been described in considerable detail such description is intended as illustrative rather than limiting as the invention may be variously embodied and as the scope of such invention is to be determined as claimed.

I claim:

1. A marker for stockings comprising a body portion and a yielding point adapted to move inwardly towards the body portion.

2. A marker for stockings comprising a body portion provided with a handle and a downwardly and forwardly extending end, a member slidably carried by said end, and yielding means for urging said member outwardly with reference to said end, said member having a pointed end adapted to operate upon the stocking.

3. A stocking marker comprising a body portion having an aperture therein, a plun-

ger slidably mounted within said aperture, and a spring positioned within said aperture and urging said plunger outwardly.

4. A stocking marker comprising a body portion having an aperture therein, a plunger slidably mounted within said aperture and having a reduced portion intermediate its ends terminating in a shoulder, a set screw threaded through said body portion adja-

cent the reduced portion of said plunger 10, cooperating with the shoulder to prevent withdrawal of the plunger.

In testimony that I claim the foregoing I have hereunto set my hand at Milwaukee, in the county of Milwaukee and State of 15 Wisconsin.

CHARLES T. LA MONT.
